UNITED STATES PATENT OFFICE.

FRANK J. LE CLAIR, OF ATTLEBORO, MASSACHUSETTS, ASSIGNOR TO FREEMAN-DAUGHADAY COMPANY, OF CHARTLEY, MASSACHUSETTS, A CORPORATION OF MASSACHUSETTS.

COLLAR-HOLDER.

1,311,821.

Specification of Letters Patent. Patented July 29, 1919.

Application filed December 19, 1918. Serial No. 287,530.

To all whom it may concern:

Be it known that I, FRANK J. LE CLAIR, a citizen of the United States, and resident of Attleboro, in the county of Bristol and State 5 of Massachusetts, have invented certain new and useful Improvements in Collar-Holders, of which the following is a specification.

This invention relates to a collar holder more particularly adapted for engaging adjacent front edges of a soft or unstarched collar, to hold them in position about the necktie.

The object of this invention is to provide such a holder with automatic gripping members at either end thereof and to so construct the holder that the fabric may be readily guided into its mouth.

This invention is an improvement over my co-pending patent application Serial No. 224,166, filed March 23, 1918.

With these and other objects in view the invention consists of certain novel features of construction, as will be more fully described, and particularly pointed out in 5 the appended claim:

In the accompanying drawings:

Figure 1— is a front view illustrating a collar with my improved holder in position thereon.

Fig. 2— is an edge view of my improved collar holder.

Fig. 3— is a front view of the holder.

Fig. 4— is a section on line 4—4 of Fig. 2, showing the band for binding the two bars 5 of the holder together.

Referring to the drawings, 10 designates the front bar of the holder which is made of resilient material preferably of metal, and having each of its ends folded back upon 0 itself as at 11 in a loop form, the extremity 12 at each end being turned outwardly on an incline toward the middle of the bar to rest upon the inner face of the back bar 13.

This back bar is preferably formed separate and independent of the front bar and of similar resilient material and is attached to the front bar by means of a short band or strap 14 which is provided with lips 15 rolled over the edges of the two bars and 0 swaged with considerable pressure to firmly and permanently fasten and retain these two bars together.

One of the advantages of this construction over a rivet connection is that both

bars being of spring material are naturally 55 hardened and therefore are more or less difficult to punch for rivet holes. Then again by applying this clasp or band to the two bars the band extends along for a distance on both sides of the middle thereof, 60 thereby stiffening both bars to some extent, permitting lighter stock to be used and at the same time providing the necessary pressure to cause one bar to bite or grip the other for firmly retaining the fabric be- 65 tween them.

It will be noted that the ends 12 of the outer bar in resting upon the inner face of the inner bar, normally holds the ends of the two bars slightly apart, thus providing 70 an open mouth as at 16 for the ready entrance of the fabric. It will also be noted that the ends 19 of the inner bar extend considerably beyond the fabric-engaging or biting point, thus forming an under projecting lip which serves to nicely guide the fabric into the open mouth to be engaged by the biting tooth or inwardly-turned end 12.

In applying a collar holder to a soft or 80 unstarched collar the operator is unable to see exactly what he is doing and so must depend somewhat on his sense of feeling. Therefore it is of importance that the device shall be readily applied to a collar. 85

In using applicant's improved collar holder it is only necessary to cause the forwardly projecting under lip to engage the inner face of the collar fabric and then by a slight endwise pressure on the holder the 90 fabric is guided directly into the mouth and is automatically engaged and firmly held by the inwardly turned end or biting tooth 12. The operation is then repeated with the opposite end and the holder is in position. 95

In removing the holder it is only necessary to catch the end of the finger under and raise the end of the outer bar after which the fabric may be readily removed without tearing or abrading.

The device is very simple and inexpensive in construction and owing to its automatic gripping action and its under projecting lip, is extremely easy to apply and will firmly retain the collar in the desired position.

The foregoing description is directed solely toward the construction illustrated,

but I reserve the privilege of resorting to all the mechanical changes to which the device is susceptible, the invention being defined and limited only by the terms of the 5 appended claim.

I claim:

10 A collar holder comprising a pair of oppositely disposed coöperating bars connected together at their middle, one of said bars being resilient and having both of its opposite ends folded back upon itself with its extremity turned outwardly on an angle in-

clined toward the middle of the bar forming a biting tooth to rest upon the inner face of the opposite bar with spring pressure thereby forming an open mouth between said bars at their ends to provide a ready entrance for the fabric. 15

In testimony whereof I affix my signature in presence of two witnesses.

FRANK J. LE CLAIR.
